UNITED STATES PATENT OFFICE.

HENRY A. WILLIAMS, OF WORCESTER, MASSACHUSETTS.

TIGHTENER FOR BOX STRAPS.

Application filed April 17, 1925. Serial No. 23,908.

To all whom it may concern:

Be it known that I, HENRY A. WILLIAMS, a citizen of the United States, residing at Worcester, in the county of Worcester and 5 State of Massachusetts, have invented a new and useful Tightener for Box Straps, of which the following is a specification.

This invention relates to a tool for use in tightening box straps, or wires, and for 10 similar purposes. The principal objects of the invention are to provide a tool of this character which will be very simple in construction and will be capable of holding one 15 end of the strap while straightening out the strap and pulling on the other end and also capable of giving a very strong pull on the strap. The invention involves improvements in details of manufacture and combinations of parts as will appear.

Reference is to be had to the accompanying drawings, in which

Fig. 1 is a side view of a box with a strap applied to it and the tool in position in which the operation starts;

Fig. 2 is a side view of the same;

Fig. 3 is a plan;

Fig. 4 is a view similar to Fig. 1, showing the completion of the operation;

Fig. 5 is a view similar to Fig. 1, showing 30 a modification in side view;

Fig. 6 is an edge view of the same;

Fig. 7 is a view similar to Fig. 5, showing the completion of the stretching operation, and

Fig. 8 is a side view showing the other 35 side of the device.

The invention is used preferably for stretching out straight and holding a metallic strap 10 or wire extending around a box 40 11. In its preferred form the invention comprises a strong handle 12 having a shaft 13 through it and an eccentric head 14 on the shaft having teeth 15 cut there on so as to constitute a clamping jaw. This shaft 45 is turned in its bearing by a wheel 16 or the like on the other end.

The handle is provided with an integral fulcrum member 17 having a widely curved operating surface projecting down from the 50 end of the handle and gradually extending away from the center. It has a flat surface 18 or jaw directly under the eccentric clamping member 14. When this eccentric clamping member is turned to the proper position 55 on its axis it will clamp the strap 10 between it and the flat surface 18. The handle

is also provided, at right angles to it, with an integral projection 20 which rests on the box at the beginning of the operation and locates the tool in proper position. 60

The operation of the device in this form is as follows:—The strap 10 is temporarily fixed to the box at one end by a nail 9 and passed around the box with its other end 22 on the edge of the top of the box. The 65 free end 22 is brought down over this end and projects out in front. The tool is rested on the box with the handle in vertical position by the projection 20 which is located at the side of the metallic band or strap 10. 70 This brings the clamping surface or jaw 18 just in alignment with the strap so that it can rest on this jaw or surface. Then the wheel 16 is turned to bring the eccentric clamping jaw 14 down on the band of metal, 75 as indicated in Fig. 1. This does not have to be turned with any hard pressure as the parts are so located that when the handle is grasped and pulled over to the right in Fig. 1 this action will cause the clamping 80 jaw 15 to clamp the strap more firmly. Now this tool is rocked over on the fulcrum member 17 to a position indicated in Fig. 4 to draw the band tight around the box. It will be seen that the fulcrum member is 85 pressed against the strap 10 and holds it in position. Now a nail 25 is inserted through two thicknesses of the strap.

A similar operation is performed in the form shown on the second sheet of the drawings. In this case the handle 30 is provided with a shaft 31 at its end on which the handle turns. On this shaft is fixed by a screw 29 the fulcrum member 32. The handle is free to move on this shaft within 90 certain limits as defined by a pin 33 on the handle and two shoulders 34 on the fulcrum member, these two shoulders being spaced apart. This fulcrum member has a curved projection 35 integral with it and also has a 95 flat surface or jaw 36 for receiving the metallic strap or band. It is provided with a second handle 38 for operating it. The main handle 30 is also provided with a jaw or surface 36 to hold the strap or wire. A 100 pivoted latch 40 is provided for holding the two handles in closed position. On the fulcrum member is a projection 41 which performs the same function as the projection 20 in the other case. 110

The operation is very similar to that in the other case. The strap being put around

the box, as before, the tool is rested on the projection 41 and the two handles disengaged from each other, the tool being held by the handle 38 so that the strap projects forward over the flat surface or jaw 36. Now the handle 30 is swung about its pivot to bring its jaw 39 down on the strap, the handle 38 being left stationary, and then the operator, grasping both handles, pulls the 10 whole tool around on the fulcrum member 35 from the position shown in Fig. 5 to that shown in Fig. 7. The results are the same as in the other case.

In both cases an immense purchase is secured by the use of the fulcrum member, the parts are started at the right point by the use of the projection 20 or 41 and the jaws get such a grip on the strap of metal that with the leverage above explained the 20 strap can be pulled in two by an ordinary workman. The parts are of simple construction and they are durable and not likely to be broken in ordinary use.

Although I have illustrated and described 25 only two forms of the invention, I am aware of the fact that other modifications can be made therein by any person skilled in the art without departing from the scope of the invention as expressed in the claims.

30 Therefore, I do not wish to be limited to these two forms of the invention but what I do claim is:—

1. In a box strap tightening device, the combination with an operating handle, of a

fulcrum member extending from the end 35 thereof in line therewith and having a convex outer operating surface at its end for engaging the end of the box, a jaw on the inner end thereof, a jaw journalled on the handle eccentrically for cooperating with 40 the first named jaw to grasp the end of a box strap, and a projection at the end of the handle extending at right angles to the length of the handle beyond the edge thereof with its lower surface in the plane of 45 the surface of the jaw on the fulcrum member to serve as a rest for the tool and hold said jaw in position to receive the box strap.

2. In a device for the purpose described, the combination of an operating handle having a jaw, a fulcrum member connected with the handle and extending therefrom in a straight line and having a convex surface on which the tool can roll in operation extending around through about a quarter circle, 50 and means on the tool projecting outwardly from the handle at right angles thereto by which it can be rested in proper place on a box to receive the end of a strap passing around the box, said fulcrum member having a jaw cooperating with the other jaw to hold the end of the strap, whereby the tool can be rocked downwardly along the vertical side of the box to stretch the strap.

In testimony whereof I have hereunto 55 affixed my signature.

HENRY A. WILLIAMS.
